UNITED STATES PATENT OFFICE.

ROY A. WEAGANT, OF NEW YORK, N. Y., ASSIGNOR, BY MESNE ASSIGNMENTS, TO
RADIO CORPORATION OF AMERICA, A CORPORATION OF DELAWARE.

APPARATUS FOR PREVENTING STATIC INTERFERENCE IN RADIOSIGNALING.

1,426,133.

Specification of Letters Patent. Patented Aug. 15, 1922.

Application filed December 12, 1917. Serial No. 206,723.

To all whom it may concern:

Be it known that I, Roy ALEXANDER WEAGANT, a citizen of the United States, and residing at Douglas Manor, county of 5 Queens, city and State of New York, have made certain new and useful Improvements in Apparatus for Preventing Static Interference in Radiosignaling, of which the following is a specification.

10 My invention relates to the art of radio signaling and has for its principal object the provision of improved receiving apparatus for reducing or preventing static interference.

15 In its preferred embodiment my invention is an improvement over the apparatus in my prior pending application Serial No. 181,458, filed July 19, 1917.

I have found by experiment, as set out in 20 detail in my said application, that atmospheric disturbances act as though propagated in a vertical direction only, whereas commercial radio signal waves travel horizontally or have a large horizontal component of motion. Consequently, static disturbances act simultaneously on the parts of a collector system which may be at the same height while commercial radio waves act simultaneously on those portions of a collector or antenna system which lie in a plane 25 at right angles to the line of travel of the waves. In my said application I have shown means whereby the effects of the atmospheric disturbances upon two parts of a collector or antenna system may be caused to 30 neutralize each other, while the effects of the signal waves act cumulatively on the receiving instrument owing largely to the fact that the antenna or collector system 35 comprises portions which are spaced apart along the line joining the receiving instruments with the source of the signal waves.

40 My present invention is an improvement on the apparatus of my said application providing a more simple arrangement in which the ends of a plurality of parts of an antenna or collector system are conductively connected in such manner as to greatly reduce the effect of the atmospheric disturbances 45 on the receiving instruments. Not only is the arrangement of my present application more simple, but I obtain even better results therefrom than from my said prior apparatus.

55 In the drawing accompanying and form-

ing a part of this specification, Fig. 1 is a diagrammatic view of a receiving station showing one form of apparatus embodying my invention, a divided collector of the general type described in my said application 60 being shown associated with receiving and detecting apparatus.

Fig. 2 of the drawing is a diagrammatic view of a modified form of apparatus in which an alternative form of antenna is employed and in which a different arrangement of adjusting devices is used.

Fig. 3 is a diagrammatic view of a third form of apparatus embodying the invention in which the detector circuit is arranged 70 differently with respect to the collector system.

Referring more particularly to the drawing 75 1-1 are looped collectors spaced apart horizontally and lying in a vertical plane which extends preferably in the direction of motion of the received signal waves. The horizontally-extending portions of each of the collectors 1-1 should preferably be similar as to horizontal extent and height 80 from the ground in order that impulses set up therein by vertically-moving radio waves or the vertically-moving components of such waves may be of equal value and occur at substantially the same instant. 2-3 and 85 4-5 are pairs of leads extending from the collectors 1, the ends of said leads being crossed and conductively joined together. In each lead I prefer to place a variable condenser such as 6, and a variable inductance 90 such as 7. Coupled to two of the inductances 7 on opposite sides of the point of connection between the leads 2-3 and 4-5 I have shown a pair of inductances such as 8, which form part of the secondary receiving 95 circuit and which are in series with a variable condenser 9 and the grid and filament of a receiver or detector 10 of any approved type—that shown being a receiver of a vacuum valve type. This detector is well-known 100 and is described in some detail herein merely for convenience of reference. The detector has a plate or cold electrode 11, as well as the filament 12 and grid 13, and the usual heating battery 14 is shown associated with 105 the filament 12. Connected between the filament 12 and plate 11 is a battery 15 in series with a telephone 16 and a variable condenser 17 in shunt with the telephone. Also connected across the plate and filament is an 110

oscillation circuit in parallel with said battery 15 and telephone 16, said oscillation circuit containing a variable capacity 18 and a variable inductance 19.

- 5 Fig. 2 is similar to Fig. 1, except that it has collectors 1¹—1¹, each having a plurality of turns or loops therein, and variable capacity condensers such as 20 are connected across the leads 2—3 and 4—5 respectively between the collectors and the variable inductances 7, condensers 20 taking the place of the condensers in series such as 6 shown in Fig. 1. The secondary circuit with the detecting and indicating devices 15 therein is shown in Fig. 2 exactly as in Fig. 1.

Fig. 3 is the same as Fig. 1, with the exception that a single coupling coil 8¹ is used in the secondary circuit instead of a 20 pair of coils such as 8 as shown in Figs. 1 and 2.

It will be seen from the foregoing that all the arrangements shown embody the principle of my said application and that 25 by reason of the arrangement in each case static disturbances are in effect balanced out or cancelled. That is to say, impulses or electromotive forces set up in the collectors 1 or 1¹ simultaneously, as by static disturbances, are made to oppose each other, where- 30 as oscillations set up by signal waves, being out of phase, act cumulatively on the detector 9.

Having thus described my invention, I 35 claim:

1. A receiving apparatus for wireless signals comprising in combination a plurality of loop collectors spaced horizontally by an appreciable fraction of a wave length and 40 having their ends so conductively connected that impulses set up simultaneously will oppose each other, and means for adjusting said collectors to the same frequency.

2. In a wireless receiving apparatus in 45 combination a plurality of looped collectors spaced horizontally by an appreciable fraction of a wave length and having their ends so connected conductively that the electrical impulses produced in one collector by

50 the vertically-moving component of electro- magnetic waves is opposed by the impulses produced by said waves in another of said collectors, and means for adjusting said collectors to the same frequency.

55 3. A receiving apparatus for wireless signals comprising in combination a plurality of looped collectors, spaced horizontally by an appreciable fraction of a wave length, said collectors having the upper horizontal 60 component of one connected to the lower horizontal component of another, and detecting means associated with said collectors.

4. A receiving apparatus for wireless signals comprising in combination a plurality 65 of collectors effectively spaced horizontally

by an appreciable fraction of a wave length, said collectors being conductively connected so that the horizontal components thereof are in opposition so that electromotive forces due to waves simultaneously received in such 70 collectors are directly opposed therein, leads connected to said collectors including inductance and capacity, and detecting means associated with said collectors.

5. A receiving apparatus for wireless sig- 75 nals comprising in combination a plurality of loop collectors spaced apart in substantially vertical planes an appreciable fraction of a wave length, the upper horizontal component of one collector being connected 80 to oppose the lower horizontal component of another, and detecting means associated with said collectors.

6. A receiving apparatus for wireless sig- 85 nals comprising in combination a plurality of loop collectors spaced apart in substantially vertical planes an appreciable fraction of a wave length and in the line of propagation of the signal waves, the upper horizontal component of one collector being 90 connected to oppose the lower horizontal component of another, detecting means associated with said collectors, and variable inductances and capacities connected to said collectors.

95 7. A receiving apparatus for wireless sig- nals comprising in combination a plurality of collector members having an effective horizontal separation of an appreciable fraction of a wave length, and directly con- 100 nected so that electromotive forces set up therein simultaneously will oppose each other, and means for adjusting said collector members to the same frequency.

105 8. A receiving apparatus for wireless sig- nals comprising in combination a plurality of collectors having an effective horizontal separation of an appreciable fraction of a wave length, the ends of said collectors being conductively connected so that impulses 110 set up simultaneously will oppose each other, detecting means associated with said collectors, and means for adjusting said collectors to the same frequency.

115 9. In a wireless receiving apparatus in combination, a plurality of collectors having an effective horizontal separation of an appreciable fraction of a wave length, the ends of said collectors being cross-connected so that the electrical impulses produced in 120 one collector by the vertically-moving component of electro-magnetic waves is opposed by the impulses produced by said waves in another of said collectors, detecting means associated with said collectors and means for 125 adjusting said collectors to the same frequency.

130 10. A receiving apparatus for wireless signals, comprising in combination, a pair of collecting members in substantial align-

- ment in the direction of desired reception, a receiving coil common to said members, and a receiving detector associated therewith, and conductive connections between 5 said collecting members and said receiving coil such that electromotive forces received simultaneously will combine differentially. 11. A receiving apparatus for wireless signals, comprising in combination, a pair 10 of collecting members in substantial alignment in the direction of desired reception, and having an effective horizontal separation of an appreciable fraction of a wave length, a receiving coil common to said members, and a receiving detector associated therewith, and direct connections from said collecting members to said receiving coil such that electromotive forces received simultaneously will combine differentially. 12. A receiving apparatus for wireless signals, comprising means for successively receiving the desired signals and for simultaneously receiving static waves, conductive connections for combining the currents due to the former and opposing the electromotive forces due to the latter effects, a detector circuit, and means for influencing said detector circuit by said combined currents due to signal waves. 13. A receiving apparatus for wireless signaling comprising a plurality of means tuned to the same frequency, for simultaneously receiving static waves; conductive connections for combining the signal currents and opposing the electromotive force due to static impulses, a detector circuit and means for influencing said detector circuits by said combined currents due to signal waves. 14. A receiving apparatus for wireless signaling comprising a plurality of collectors extending horizontally an appreciable fraction of a wave length, adapted to be simultaneously affected by static waves, con- 50 ductive connections for combining the signal currents and opposing the electromotive forces due to the static waves, a detector circuit and means for influencing said detector circuit by said combined current due to signal waves. 15. A receiving apparatus for wireless signaling comprising the combination of a pair of collecting members tuned to the same frequency, a receiving coil connected to said members, a receiving detector associated therewith, and conductive connections from each of said collecting members to said receiving coil, such that electromotive forces received simultaneously will combine differentially. 55 16. A receiving apparatus for wireless signals, comprising in combination, a plurality of horizontally disposed collecting members having an effective separation of an appreciable fraction of a wave length where- 60 by desired waves are received successively and static waves simultaneously, a primary receiving coil for said collecting members, a secondary receiving circuit associated therewith, and connections for the collect- 65 ing members through the primary coil, to points of equal and opposite potential for impulses received simultaneously by said collectors, whereby static impulses set up therein simultaneously will oppose and pro- 70 duce a minimum effect on said secondary circuit. 17. At a receiving station, an antennae system extending horizontally an appreciable fraction of a wave length comprising 75 80 directive portions directively arranged and conductive connections between said portions whereby electromotive forces due to signal waves received in a given order are combined, and electromotive forces due to disturbances simultaneously received are opposed therein.

ROY A. WEAGANT.
